INHALATION DEVICE

Henri Adolphe Gilquin, Ain-Seba, near
Casablanca, MoroccoApplication December 27, 1932, Serial No. 649,054
In Morocco January 27, 1932

3 Claims. (Cl. 128—185)

The object of the present invention is to permit, in a simple and rational manner, of the inhalation of pure air, either natural or treated, for instance dried or super-oxygenated or mixed 5 with medicinal or other products.

To this effect, in accordance with the invention, the air intended for inhalation is supplied to a container and is forced to diffuse slowly and regularly through a partition, permeable to air 10 over the whole or part of its surface, on which rests the head of the person (or persons) undergoing treatment, by preference in the recumbent position, the other walls of the said container being impermeable to air.

15 The device forming the subject of the invention is composed, in principle, of a pillow, cushion or other article, only the upper wall of which, intended to support the head of the person (or persons) undergoing treatment, is permeable to air, 20 either over the whole of its surface or in certain zones only. The air, the admission of which to the interior of the device is effected through one of the non-permeable faces, is slowly and regularly diffused through the permeable wall on 25 which the head of the person rests and surrounds the said head with a zone of pure air constantly renewed, the vivifying effect of which is particularly effective and benignant.

In comparison with installations by which it is 30 sought to obtain the general treatment of the whole of the atmosphere of a room at the same time, the invention represents an important progress. In point of fact, in the case of the said installations, the large volumes of air to be treated 35 and put into circulation entail heavy expense; moreover, it is very difficult to manage to homogenize the air of a room perfectly, in view of the fact that dead zones are produced there; finally it is impossible to adapt the treatment and the 40 supply of the air to the particular requirements of each person. These drawbacks are eliminated by the device in accordance with the invention, which device relieves, moreover, immediately and completely, the person of his expirations and presents a possibility of regulating the supply of air 45 at will.

One form of constructing the device is shown 50 diagrammatically, by way of example by no means limitative, in the annexed drawing, to which reference will be made in the following description.

Fig. 1 is a view in vertical longitudinal section 55 of an example of installation comprising the application of the device.

Fig. 2 is a ground plan of a form of construction of the device.

Fig. 3 is a view in vertical section following A—A on Fig. 2 and

Fig. 4 a view in vertical section following B—B 5 on Fig. 2.

In the drawing, 1 is a container composed, for instance, of a cushion or pillow, 2 the springs, on the upper wall 1^a of which will rest the head of the person (or persons) who is to inhale and 10 which, by preference, is extended, it being possible and advantageous to carry out the treatment during sleep.

The upper wall 1^a is permeable to air and to this end it may be composed, for instance, of a 15 metallic net covered with a permeable cloth.

The other walls, such as 1^b, 1^c, 1^d, are, on the other hand, impermeable to air being, for such purpose, of wood or of a close fabric.

The air, aspirated by a fan 3, traverses, as required, one or more purifying and treating devices 4 and is forced into the interior of the container 1, a regulating device 5 being provided in order to permit of varying and regulating the 20 volume of air admitted. 25

The regulation of the supply of air may be effected at will by regulating the speed of the fan 3 by means of a device causing the power at the terminals of its driving motor to be varied.

The wall 1^a may be permeable over the whole 30 of its surface or have certain permeable zones only, by preference for the portion of the head in the region of the nose.

In the form of construction represented by 35 Figs. 2 to 4, the head support, carried out in the form of a pillow, is composed of a frame 10, of wood or metal, constituting an inside fitting entirely surrounded by an envelope 16 of a fabric such as closely woven and thick cloth, practically 40 impermeable to air.

The upper surface of the pillow is provided with two orifices 11 and 12, cut from a spot where they will be located practically adjacent to the nose when the head of a person in a recumbent position rests on the pillow, and fitted with a fine metallic cloth 13, or equivalent, this cloth regulating the diffusion of the air. 45

A loose cover 14 of washable meshed fabric, of the kind, for instance, known under the name 50 of "Cellular" fabric, fixed at the sides, for instance, by press studs 15, covers the upper part and contributes, by reason of its construction, in regulating the diffusion of the air.

It is understood that it is possible, without 55

departing from the scope of the invention, to conceive variants and improvements in details.

I claim:

- 5 1. A head supporting device constituting a pillow and comprising an open framework, an envelope formed of material substantially impervious to the passage of air and enclosing said framework, said envelope having a top head supporting portion provided with an opening on each side of the longitudinal axis thereof, foraminous metallic members arranged in said openings and permitting the passage of air therethrough, and means for supplying air to the interior of the envelope.
- 10 15 2. A head supporting device as claimed in claim 1, characterized in that said envelope forms an internal chamber containing air, and

spring means resiliently sustaining the head supporting portion of the envelope.

3. A head supporting device constituting a pillow and comprising an open framework, an envelope including said framework and formed of material substantially impervious to the passage of air, said envelope having a top head supporting portion provided with openings, one opening being arranged at each side of the center of the envelope top, a foraminous metal member arranged in each opening and controlling the passage of air therethrough, and an air supply pipe connected to the interior of said envelope and having a cross sectional area substantially less than each of said openings.
